(57) **CLAIM**

The ornamental design for a headgear, as shown and described.

DESCRIPTION

FIG. 1 is perspective view of a headgear according to an embodiment of my design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view shown in use.

Where included, broken lines showing environment or structure are for illustrative purposes only and form no part of the claimed design. FIGS. 1, 2, 3 and 8 show stitching in broken lines which form no part of the claimed design.
